DEVICE FOR SUPPLYING CURRENT TO THE BOTTOM OF ELECTROLYTIC FURNACES

Pio Pontremoli, Milan, Italy, assignor to Montecatini Società Generale per l'Industria Mineraria e Chimica, Milan, Italy, a corporation of Italy

Application November 10, 1954, Serial No. 468,120

Claims priority, application Italy November 17, 1952

5 Claims. (Cl. 204—243)

My invention relates to devices for supplying electric current to the bottom of electrolytic furnaces, particularly to the cathodic bottom of aluminum electrolysis furnaces.

Considerable difficulties have been encountered in securing a uniformly distributed supply of current to the cathodic bottom of electrolytic furnaces, particularly for aluminum electrolysis in a melt of cryolite and alumina, because the current has the tendency to distribute itself irregularly over the individual areas of the bottom regardless of whether the bottom is composed of carbon blocks or of tamped carbon paste or compound.

A uniform current distribution and density in the cathodic bottom of an aluminum furnace, however, is desirable for attaining optimum durability of the bottom structure itself and for securing most favorable consumption of the anode or anodes above the furnace bottom. The furnace bottom represents a large proportion in cost of the entire furnace; and only by avoiding the occurrence of current concentrations at singular points and thus local overheating of the bottom can optimum life of the bottom and maximum regularity and economy of furnace operation be achieved.

It is an object of my invention, therefore, to improve the current-supply devices so as to secure a virtually perfect uniformity of current density in the furnace bottom without appreciable complication in furnace design and without entailing the increased susceptibility to injurious ingress of air encountered with past attempts at improving current distribution. It is another, more specific object of my invention, to secure the desired uniformity of current distribution with the aid of a horizontal arrangement of cathode conductors entering from the side into the furnace bottom.

This and more specific objects of my invention as well as the means for achieving them will be apparent from the following description taken in conjunction with the drawings in which:

Figs. 1a and 1b show a longitudinal section and cross section respectively of a furnace bottom portion according to the invention, and Figs. 1c and 1d are coordinate diagrams of current distribution;

Fig. 2a is a longitudinal section through a bottom portion according to another embodiment of the invention, and Figs. 2b and 2c are explanatory diagrams of current distribution curves.

Fig. 3 is a vertical longitudinal section through a furnace embodying the device of Fig. 2a.

In Figs. 1a, 1b and in Fig. 2a, the layer of molten aluminum is denoted by 11, while 12 denotes a portion of the furnace bottom consisting of a block or a tamped mass of carbon material. Embedded in the bottom portion are a cathode conductor 13 of iron and a bus bar 14. According to Fig. 1a, the bus bar is connected with the cathode conductor in a single central zone of the latter and may form an integral piece together with the conductor. In the embodiment of Fig. 2a, the bus bar 14 is joined with the cathode conductor 13 in two zones longitudinally spaced from each other. Depending upon the length of

the furnace bottom in the direction of the bus bars, more than two junction zones may be provided.

If desired, each bus bar 14 and each connecting zone may be electrically insulated from the carbon material of the furnace bottom, as shown at 17 in Figs. 1a, 1b and 2a, to prevent a direct passage of current from the bus bar to the cathodic bottom. The insulation 17 may consist of a sheet of asbestos, a layer of heat-proof cement, mica or any other insulating material resistant to temperatures of 800° C. or more.

The current distribution within the carbonaceous furnace bottom above the cathode conductor is in accordance with curves 15 in the diagrams of Figs. 1d and 2c. The current distribution at the contact surface between 15 furnace bottom and molten aluminum is as shown by curve 16 in Figs. 1c and 2b.

As these diagrams show, an excellent uniformity of current distribution and current density is secured and, as mentioned, a further improvement in this respect can be 20 obtained by providing more than two junction zones suitably spaced from each other.

In a cathode and bus bar system according to the invention, the bus bars of the furnace bottom extend all to the side of the bottom so that it is unnecessary to resort 25 to special and cumbersome expedients for securing a reliable sealing against ingress of air.

Fig. 3 illustrates a furnace or cell for production of aluminum, employing the cathode structure 13, 14, 17 of Fig. 2a. At 20 is the conventional anode, usually of carbonaceous material. The anode is ordinarily movably supported, for upward and downward motion, and has iron conductor rods 21, 22 embedded therein.

I claim:

1. A molten bath furnace for igneous electrolysis of aluminum, comprising a cathodic bottom portion supporting the molten bath and a consumable anode above the bottom portion, the bottom portion comprising a block of carbonaceous material having a horizontal top surface for contact with the aluminum and having a bottom surface and lateral side surfaces, a cathode conductor of metal fully embedded in said material and extending parallel to said top surface, a bus bar of metal laterally extending from the outside through one of said side surfaces to within said block and being located beneath said cathode conductor and adjacent to said bottom surface in parallel and spaced relation to said conductor, the bus bar being enclosed in the carbonaceous block at its upper face, the lower face of the bar being exposed along the bottom surface of the block, and connecting means joining said bus bar with said cathode conductor within said bottom portion and extending upwardly between said bar and conductor in spaced relation from the ends of said conductor, said connecting means being integrally formed with said bus bar and conductor, whereby the conductor is supported by the bus bar and the current from said bus bar is uniformly distributed from said cathode conductor through said carbonaceous material to said top surface.

2. A molten bath furnace for igneous electrolysis of aluminum, comprising a cathodic bottom portion supporting the molten bath and a consumable anode above the bottom portion, the bottom portion comprising a block of carbonaceous material having a horizontal top surface for contact with the aluminum and having a bottom surface and lateral side surfaces, a cathode conductor of metal fully embedded in said material and extending parallel to said top surface, a bus bar of metal laterally extending from the outside through one of said side surfaces to within said block and being located beneath said cathode conductor and adjacent to said bottom surface in parallel and spaced relation to said conductor, the bus bar being enclosed in the carbonaceous block at its upper face, the lower face of the bar being exposed along the

bottom surface of the block, and a plurality of connecting sections spaced lengthwise of and joining said bus bar with said cathode conductor within said bottom portion and extending upwardly between said bar and conductor in spaced relation from the ends of said conductor, said connecting means being integrally joined with said bus bar and conductor, whereby the conductor is supported by the bus bar and the current from said bus bar is uniformly distributed from said cathode conductor through said carbonaceous material to said top surface.

3. A molten bath furnace for igneous electrolysis of aluminum, comprising a cathodic bottom portion supporting the molten bath and a consumable anode above the bottom portion, the bottom portion comprising a block of carbonaceous material having a horizontal top surface for contact with the aluminum and having a bottom surface and lateral side surfaces, a cathode conductor of metal fully embedded in said material and extending parallel to said top surface, a bus bar of metal laterally extending from the outside through one of said side surfaces to within said block and being located beneath said cathode conductor and adjacent to said bottom surface in parallel and spaced relation to said conductor, the bus bar being enclosed in the carbonaceous block at its upper face, the lower face of the bar being exposed along the bottom surface of the block, and connecting means joining said bus bar with said cathode conductor within said bottom portion and extending vertically between said bar and conductor in centrally spaced relation from the ends of said conductor, said connecting means being integrally joined with said bus bar and conductor, whereby the current from said bus bar is uniformly distributed from said cathode conductor through said carbonaceous material to said top surface.

4. A furnace for igneous electrolysis of a molten bath, comprising a cathodic bottom portion supporting the molten bath and a consumable anode above the bottom portion, the bottom portion comprising a mass of electroconductive material having a top surface for contact with the molten bath and having a bottom surface and lateral side surfaces, a cathode conductor of metal fully embedded in said material and extending parallel to said top surface, a bus bar of metal laterally extending from the outside through one of said side surfaces to within said mass and being located beneath said cathode conductor and adjacent to said bottom surface in parallel and spaced

relation to said conductor, the bus bar being enclosed in the said mass at its upper face, the lower face of the bar being exposed along the bottom surface of the mass, and connecting means joining said bus bar with said cathode conductor within said bottom portion and extending upwardly between said bar and conductor in symmetrically spaced relation from the ends of said conductor, said connecting means being integrally joined with said bus bar and conductor, whereby the current from said bus bar is uniformly distributed from said cathode conductor through said electroconductive material to said top surface.

5. An electric furnace for molten materials, comprising an electrodic bottom portion supporting the molten material, the bottom portion comprising a mass of electroconductive material having a horizontal top surface for contact with the aluminum and having a bottom surface and lateral side surfaces, a metal conductor fully embedded in said electroconductive material and extending parallel to said top surface, a bus bar of metal laterally extending from the outside through one of said side surfaces to within said mass and being located beneath said conductor and adjacent to said bottom surface in parallel and spaced relation to said conductor, the bus bar being enclosed in the said mass at its upper face and along the sides, the lower face of the bar being exposed along the bottom surface of the mass, and connecting means joining said bus bar with said conductor within said bottom portion and extending upwardly between said bar and conductor in symmetrically spaced relation from the ends of said conductor, said connecting means being integrally joined with said bus bar and conductor, whereby the conductor is supported by the bus bar and the current from said bus bar is uniformly distributed from said conductor through said carbonaceous material to said top surface.
